Attorney

UNITED STATES PATENT OFFICE.

JOHN A. CHAMBERS, OF NEWBURG, MISSOURI, ASSIGNOR OF ONE-HALF TO JAMES A. CLARK, OF NEWBURG, MISSOURI.

PIPE.

Application filed May 11, 1921. Serial No. 468,566.

To all whom it may concern:

Be it known that I, JOHN A. CHAMBERS, a citizen of the United States, residing at Newburg, in the county of Phelps and State 5 of Missouri, have invented a new and useful Pipe, of which the following is a specification.

The device forming the subject matter of this application is a tobacco pipe, and the 10 invention aims to provide novel means whereby the saliva or water of condensation may be segregated and kept out of the bowl of the pipe, the contents of the bowl never becoming sodden, and a dry smoke being 15 assured, it being practically impossible for the operator to draw material which has accumulated in the pipe into his mouth, whilst he is smoking.

It is within the province of the disclosure 20 to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that within 25 the scope of what is claimed, changes in the precise embodiment of the invention shown 30 can be made without departing from the spirit of the invention.

In the accompanying drawings:—

Figure 1 shows in longitudinal section, a 35 device constructed in accordance with the invention; Figure 2 is a top plan wherein parts are broken away; and Figure 3 is a cross section on the line 3—3 of Figure 1.

The device forming the subject matter of 40 this application may be used in connection with pipes of various kinds. If desired, the invention may be embodied in a pipe of the kind shown in the drawings, the bowl of the pipe being marked by the numeral 1 and the numeral 2 designating the stem, the bowl 45 1 having a chamber 3. A mouth piece 4 is provided, if desired, and the mouth piece may be assembled with the stem 2 in any desired way. As shown, but not of necessity, 50 the mouth piece 4 has a reduced tip 5 threaded into the stem 2.

There is provided a receptacle 6 which is detachably mounted on some portion of the pipe. If desired, the receptacle 6 may be

threaded into the lower portion of the bowl 55 1, at the point where the bowl joins the stem, although it might be desirable to locate the receptacle in some other way. The stem 2 and the mouth piece 4 have a bore 7 which leads to the receptacle 6. 60

The numeral 8 denotes an angular smoke conduit, including a long branch 9 and a short branch 10. The long branch 9 is mounted detachably at one end in the bowl 1 and communicates with the chamber 3. 65 The branch 9 of the smoke conduit 8 may carry a finishing plate 11 which bears against the outer surface of the bowl 1. The inner end of the short branch 10 of the smoke conduit 8 passes through a portion of the stem 2 and communicates with the bore 7, the branch 10 being mounted in a ferrule 12, surrounding the end of the stem 2. A notch 70 14 is fashioned in the end of the stem 2. In the assembling of the smoke conduit 8 with the pipe, the conduit is moved in the direction of the arrow A in Figure 1 until the end of the long branch 9 enters the opening provided for its reception in the bowl 1, the finishing plate 11 abutting against the 75 outer surface of the bowl. By this same operation, the extremity of the branch 10 of the smoke conduit is carried into the notch 14 in the stem 2. The ferrule 12, being assembled with the branch 10 by the operation 80 above alluded to, is mounted on the end of the stem 2 and closes the notch 14, so that the notch is not visible from the outside of the pipe. Although this method and means for mounting the end of the branch 10 in 85 place is useful and desirable, it is not insisted upon. A clean-out plug 15 is threaded into the branch 10 of the smoke conduit 8, in alinement with the branch 9, a clean-out plug 16 being threaded into the branch 9 90 in alinement with the branch 10. It is obvious that the plug 15 gives access to the branch 9, for cleaning, the plug 16 exercising a like office with respect to the branch 16.

In practical operation, the smoke is drawn 100 through the conduit 8 and traverses so much of the bore 7 as is located in the mouth piece 4. The saliva or water of condensation follows the bore 7 and is received in the receptacle 6, it being possible to detach the 105 receptacle at any time and to clean the same out. The pipe is so constructed that a cool clean dry smoke will be afforded at all times,

the bowl of the pipe never accumulating the wet and noisome mass of unconsumed tobacco or ashes.

I claim:

1. In a device of the class described, a pipe comprising a bowl and a stem, the stem having a bore; a receptacle detachably assembled with the pipe and communicating with the bore adjacent to the inner end of the bore; an external conduit including angularly disposed branches mounted respectively in the bowl and in the stem, one branch communicating with the interior of the bowl and the other branch communicating with the bore of the stem; and a closure member mounted in each branch and giving access to the other branch.

2. A pipe comprising a bowl and a stem, the stem having a bore, and being provided in its end with a notch leading to the bore; a ferrule surrounding the stem and closing the notch; and a smoke conduit carried by

the ferrule, the forward end of the conduit communicating with the bowl, and the rear end of the conduit communicating with the bore of the stem, the rear end of the conduit being located in the notch.

3. In a device of the class described, a pipe comprising a bowl and a stem, the stem having a bore, and being provided in its end with a notch leading to the bore; a smoke conduit, the forward end of which communicates with the bowl, the rear end of which communicates with the bore of the stem, the rear end of the conduit being located in the notch; and a ferrule surrounding the stem and constituting a closure for the notch.

In testimony that I claim the foregoing as my own, I have hereto affixed my signature in the presence of two witnesses.

JOHN A. CHAMBERS.
